COMBINED TELEPHONE CABINET AND DIRECTORY HOLDER

Rollie B. Nawman, Oakland, Calif., assignor to Benner-Nawman, Inc., Oakland, Calif., a corporation of California

Application April 4, 1958, Serial No. 50,336

Term of patent 14 years

(Cl. D13—1)

The portions shown in broken lines are for purposes of illustration only.

I claim:

The ornamental design for a combined telephone cabinet and directory holder, substantially as shown and described.
